UNITED STATES PATENT OFFICE.

CHARLES F. TUCKER, OF HARTFORD, CONNECTICUT.

OIL-HOLE COVER.

1,134,025.

Specification of Letters Patent. Patented Mar. 30, 1915.

Application filed November 11, 1913. Serial No. 800,309.

To all whom it may concern:

Be it known that I, CHARLES F. TUCKER, a citizen of the United States, residing at Hartford, in the county of Hartford and 5 State of Connecticut, have invented certain new and useful Improvements in Oil-Hole Covers, of which the following is a specification.

This invention relates to oil-hole covers, 10 one of the objects of the invention being the provision of an article of this character which is simple in construction, can be inexpensively and readily made and which is thoroughly dust-proof.

15 In the drawings accompanying and forming part of the present specification I have shown in detail one of the several convenient forms of embodiment of the invention which to enable those skilled in the art 20 to practice the same will be set forth fully in the following description. I do not restrict myself to this disclosure; I may depart therefrom in several respects within the scope of the invention defined by the claim 25 following said description.

Referring to said drawings: Figure 1 is a 30 view of the article, the plug member being in elevation and the cap member being shown in section and also retracted, and, Fig. 2 is an elevation of the same.

Like characters refer to like parts in both views.

An oil-hole cover embodying the invention 35 comprises a plug member as 2 and, a cap or closure member as 3, the plug member being usually provided as a means for mounting the device in position, for which purpose its forward or inner end is properly shaped. This forward end after the usual fashion 40 may be plain, threaded or otherwise formed. As shown it is threaded as at 4, has a longitudinal bore or passage 5 intersected by the port 6 and also has at its outer or upper end or at any other convenient place, a suitable 45 abutment which as shown consists of an integral collar or flange 7. This abutment or flange presents a suitable bearing for a spring which also acts against a suitable 50 abutment as will hereinafter appear on the cap or closure member 3. Said plug member as thus far described, is comparatively common, and no claim is made to the same

per se. The cap member 3 is shown as being of one piece, having an open forward end and a closed rear end and as imperforate 55 throughout its entire extent, the body thereof inclosing the coiled spring 8 which as shown encircles the outer portion of the plug member 2, one end of the spring bearing against the abutment 7 and the other end against the 60 abutment 9 on the cap member 3, said abutment 9 as shown consisting of an inwardly bent or turned annular flange. The spring 8 is of protractile or push type and it exerts a constant tendency to advance the cap member 65 3, by reason of which the body thereof normally closes the port or oil introducing opening 6 at which time the outer closed end of the cap member has a bearing directly against the plug member. When the cap 70 member is in its normal position, the port is wholly closed or covered and the same observation applies in fact to about half of the plug member; or at least the forward portion of the cap member should preferably 75 extend beyond the port 6 to make the oil-hole cover virtually dust-proof. To supply oil to a bearing or other part the cap member 3 is drawn back an extent sufficient to uncover or partially uncover the port 6 to 80 receive the snout of an oil-can which can be utilized for holding said cap member in its backward position sufficiently to supply the necessary amount of oil. When this is done 85 the cap member will be released and will be instantly advanced to its initial position by the spring 8. When the plug member is screwthreaded as at 4 it forms a polygonal portion thereupon to receive a wrench, and this can be conveniently secured by the opposite flat faces 10 on said plug member. It should be noted that the interior of the cap member from the outer closed end thereof to 90 the abutment 9 is of uniform diameter.

What I claim is:

An oil-hole cover having a plug member, and a cap member, the cap member having the forward end open and the rear end wholly closed, said closed end being integral with the body of the cap member, a 100 coiled spring surrounding the plug member, the cap member having an abutment for one end of the spring, the plug member having an abutment for the other end of the spring,

the plug member having a bore and also having a port opening into said bore, said spring serving to constantly advance the cap member to cause the body thereof to normally close the port and the outer end of the plug member when the cap member is advanced, having a bearing directly against said closed end of the cap member and the interior of

the cap member from its outer closed end to its abutment being of uniform diameter. 1.

In testimony whereof I affix my signature in presence of two witnesses.

CHARLES F. TUCKER.
